UNITED STATES PATENT OFFICE.

HUGH ALVIN LONGINO, OF LA GRANGE, KENTUCKY.

CINDER-GUARD FOR CAR-WINDOWS.

1,200,376.

Specification of Letters Patent.

Patented Oct. 3, 1916.

Application filed October 30, 1915. Serial No. 58,846.

To all whom it may concern:

Be it known that I, HUGH ALVIN LONGINO, citizen of the United States, residing at La Grange, in the county of Oldham and State of Kentucky, have invented certain new and useful Improvements in Cinder-Guards for Car-Windows, of which the following is a specification, reference being had to the accompanying drawings.

This invention relates to an improved cinder guard for car windows and has for its primary object to provide means which will effectually prevent flying cinders from entering the open windows of a coach and falling upon the passengers and possibly in the eyes with serious injury thereto.

The invention has for another important object to provide a wire screen guard for car windows which, while preventing the cinders from entering the window, will at the same time permit a constant steady flow of fresh air to enter.

My invention has for an additional object to simplify the construction of devices of the above character and enable the same to be readily applied to train coaches at nominal expense.

With the above and other objects in view, my invention consists in the novel features of construction, combination and arrangement of parts to be hereinafter more fully described, claimed and illustrated in the accompanying drawing, in which,

Figure 1 is a side elevation showing my improved cinder guards applied to a car; Fig. 2 is a perspective view showing the framework upon which the screen is secured; and Fig. 3 is an enlarged sectional view taken on the line 3—3 of Fig. 2.

Referring in detail to the drawing, 5 designates a passenger coach and 6 the windows thereof. Upon the window casing or framework between the openings in the car wall, my improved cinder guard is secured.

In carrying out my invention, I have found, as an economical construction, the combination and arrangement of the several parts illustrated, which include a frame indicated at 7 formed from rods of proper thickness or diameter. This frame includes three longitudinally disposed rods 8 which are so arranged and connected together at intervals by the rod 9 as to form a triangular figure in plan. The longitudinally extending rods are provided with eyes or other

means to receive screws or fasteners indicated at 10, whereby the frame can be rigidly secured upon the outer face of the window frames between the adjacent windows. The opposite sides of the triangular frames 7 are entirely covered by a wire mesh screen shown at 11. A central vertical strip of fine wire gauze 12 bisects this frame and extends from the central longitudinal frame rod to the wall of the car. These wire screen guards constructed in the manner stated, extend over the sill of the window to the upper end thereof so that they form a complete protection at all points along each side of the window opening.

From the above description, the operation of the device will be clearly understood. In the movement of the train, flying cinders driven by strong air currents will strike against the sloping or inclined reticulated side walls of the guards and either fly outwardly from the window or enter through the screen fabric and be caught by the vertical strip of wire gauze 10. The air may, however, freely pass through this gauze and the opposite reticulated side wall of the guard and enter the adjacent open window so that there will be an unrestricted, steady supply of fresh air to the interior of the car. The ordinary fender of this character is usually in the form of a solid metal plate set at an angle and projecting outwardly from the car wall. These plates, however, interfere with the free flow of the air so that it will enter the window in gusts and the plates not only do not prevent the cinders from entering the windows but, on the contrary, they frequently act as directing means to deflect the cinders into the window opening.

The several guards at their lower ends are entirely open so that the cinders will fall downwardly therethrough below the windows.

It will thus be seen that I have provided a very simple, effective and reliable cinder guard for car windows which is also exceedingly simple in its construction and may be applied to the cars at nominal expense.

While I have shown and described the preferred construction and arrangement of the several parts employed, it is to be understood that the invention is susceptible of considerable modification therein and I, therefore, reserve the privilege of adopting

all such legitimate changes as may be fairly embodied within the spirit and scope of the invention as claimed.

Having thus fully described my invention, 5 what I desire to claim and secure by Letters Patent :—

1. A cinder guard for car windows including vertically disposed, perforate walls fixed to the car between adjacent windows 10 and converging toward each other, and means centrally arranged between said walls and extending the entire length thereof to prevent the passage of cinders in a horizontal line through the space between said perforate walls.

2. A cinder guard for car windows including a vertically disposed frame secured to the outer face of the car wall between adjacent windows and having outwardly extending, convergently disposed side walls, wire screen fabric covering said side walls throughout the length of the frame, and a

medial vertically extending strip of finer wire gauze arranged between the meeting edges of the converging side walls and the 25 wall of the car.

3. A cinder guard for car windows including a vertically disposed frame of triangular form in plan secured to the outer face of the car wall between adjacent windows, the apex of said frame being centrally disposed between the car windows and spaced from the car wall, a vertical strip of fine wire gauze bisecting said frame and extending from the apex thereof to the car 30 wall, and relatively coarse wire screen fabric covering the opposite inclined sides of said frame throughout the length thereof.

In testimony whereof I hereunto affix my signature in the presence of two witnesses. 40

H. ALVIN LONGINO.
